UNITED STATES PATENT OFFICE

CHARLES PASCAL, OF MONTREAL, QUEBEC, CANADA

RAIL JOINT

Application filed February 8, 1928, Serial No. 252,821. Renewed November 21, 1930.

This invention relates to a rail joint of the type that includes a base plate extending beneath and supporting the base of adjacent rail ends and in which a joint plate is rigidly secured to said base plate such as is shown in my prior Patents, #1,399,572 of December 6, 1921, #1,442,291 of January 16, 1923, and #1,517,124 of November 25, 1924, upon which this invention is an improvement.

10 A principal object of this invention is to provide a rail joint including means to cause that side of the head of the rail that faces the flange of the wheel to be slightly inclined inwardly away from said flange so that the liability of the flange engaging a rail head that is slightly out of alignment is reduced to a minimum.

15 A further object of this invention is to provide a rail joint, including a base plate that normally extends beneath and supports the rail ends, and a joint plate secured in lapped relation to said base plate, in which the removal and insertion of the securing means that passes through the lapped portions of said plates is facilitated.

20 A still further object of this invention is to provide a rail joint including a base plate, arranged beneath the ends of adjacent rails, that is provided with means to cause said plate to penetrate the surface of the underlying ties when secured thereto, in such manner that creeping of the base plate relative to the ties is prevented.

25 Still further objects of this invention will appear as a description thereof proceeds with reference to the accompanying drawings in which,

Figure 1 is a sectional view through a rail adjacent the improved joint of this invention.

30 Figure 2 is a perspective view of the base plate.

Figure 3 is a perspective view of the joint plate that is attached to the base plate.

35 Figure 4 is a side view of the base plate shown in Figure 2, viewed from the left side of said figure.

Like reference characters indicate like parts throughout the several views.

40 The numeral 5 indicates a base plate formed to rest upon adjacent ties and to re-

ceive the adjacent ends of a pair of rails. One of these rails is designated by the numeral 6 on Figure 1. Base plate 5 is provided adjacent one side thereof with a flange 7 overhanging a portion of a supporting surface 8 of the base plate. Said flange is spaced above said supporting surface and provides a recess 9 to snugly receive a portion 10 of the base of each of the adjacent rails.

45 The supporting surface 8 of the base plate 5 is slightly inclined toward the recess 9 as indicated on Figure 1. This inclination is formed by providing the base plate 5 that is of gradually increasing thickness from the side thereof that carries the flange 7 toward the other side of the base plate. It will be apparent that by this arrangement the rails 6 are supported so that they are slightly inclined with respect to the vertical. Accordingly, the side 11 of the head 12 of rail 6 that engages the flange of the car wheels, one of which is shown at 13 in Figure 1, is slightly inclined away from the flange 14 of said wheel.

50 Base plate 5 is provided in its undersurface with a series of grooves 15 (Fig. 4) positioned and formed to bite into the ties arranged therebeneath, when the base plate is attached to the ties whereby creeping of the base plate with respect to the tie is prevented. If desired, these grooves may be made in any other manner that will provide projections that can be forced into the ties that underlie the base plate.

55 The side of the base plate 5 opposite the flange 7 is offset upwardly as shown at 16 and is provided with a plurality of elongated slots 17 disposed at suitable intervals along said offset portion.

60 The adjacent ends of the rails that are arranged upon the base plate 5 are rigidly secured together by a pair of joint plates 18 and 19 disposed on opposite sides of the rails between the head and base thereof as clearly shown in Figure 1. Said plates are rigidly clamped together with the web of the rail between them, by bolts 20 extending through oval openings 21 and 22 in the plates 18 and 19 respectively, and through an enlarged

opening 23 in the web of the rail. The plates 18 and 19 and the rail are rigidly clamped together by a nut 24 threaded on the end of bolt 20 and a lock nut 25.

5 Joint plate 18 is provided with a tongue 26 and an offset side 27 arranged to lie over the offset portion 16 of the base plate 5. The offset portion of the joint plate 18 is provided with a plurality of spaced elongated openings 28 arranged to register approximately with the openings 17 in the base plate 5. It will be observed by a comparison of Figs. 2 and 3 that the major axes of the elongated openings 17 in base plate 5 and of the elongated openings 28, just described, extend at right angles to each other. This arrangement permits the openings to be readily brought into registry to receive bolts 29, the heads 30 of which are arranged in the space provided by the offset 16 in the base plate 5. The bolt 29 is provided with a non-circular shank adjacent the head thereof, said non-circular shank being arranged to enter the elongated openings 17 in the base plate 5, 25 so that the rotation of the bolt will be prevented when the nuts 30 and 31 are adjusted to rigidly clamp the base plate 5 and the joint plate 18 together with a portion of the base of adjacent rails between them.

30 By supporting the rail in a slightly inclined position so that the face 11 of the head thereof recedes away from the flange 14, the likelihood of rupturing the rail joint by the wheel flanges, if the adjacent rails 35 are slightly out of alignment is greatly reduced, since the face 11 of the improperly aligned rail is largely out of the path of the flange 14, so that the shock applied to the improperly aligned rail by the flanges of the wheels is reduced to a minimum. By offsetting the ends of the base and joint plates, as above described, the entry of the securing bolts 30 is greatly facilitated and by providing the base plate with grooves 15, forming, in effect, teeth that bite into the surface of the ties, creeping of the base plates relative to the ties is substantially prevented.

The invention may be embodied in other specific forms without departing from the spirit or essential characteristics thereof. The present embodiment is therefore to be considered in all respects as illustrative and not restrictive, the scope of the invention being indicated by the appended claims rather than by the foregoing description, and all changes which come within the meaning and range of equivalency of the claims are therefore intended to be embraced therein.

What I claim as my invention is:

50 1. A rail joint comprising a base plate that is of substantially the same cross section at all points along the length thereof arranged beneath the adjacent ends of a pair of rails and having a recess to receive a portion of the base of the rails and an uninterrupted in-

clined rail supporting surface extending away from said recess, and rail joining means secured to said rails and extending across the joint therebetween, said rail joining means being provided with a longitudinal shoulder coextensive therewith and abutting a shoulder on the base plate and secured to said base plate.

55 2. A rail joint comprising rail joining means including an upwardly offset portion and a base plate extending beneath and supporting adjacent rail ends and including a recess to receive a portion of the rail bases and another upwardly offset portion snugly underlying said first named portion and formed for attachment to said rail joining means, said plate being provided with means on its under surface formed to engage a tie to prevent movement of said plate relative to said tie in a direction transverse of said tie.

60 3. A rail joint comprising rail joining means and a base plate extending beneath and supporting on its top surface adjacent rail ends and including a recess to receive a portion of the rail bases and another portion formed for lapping interlocking with and for attachment to said rail joining means, said plate being provided with grooves in its under surface extending transversely of said rails.

65 4. A rail joint comprising a rail joint plate and a base plate extending beneath and supporting adjacent rail ends, one side of said base plate embracing a portion of the rail bases and the other side of said base plate being offset upwardly, said joint plate being offset and overlying the offset side of said base plate, and means to secure said base and joint plates together through said offsets.

70 5. A rail joint comprising a rail joint plate and a base plate extending beneath and supporting adjacent rail ends, one side of said base plate embracing a portion of the rail bases and the other side of said base plate being offset upwardly, said joint plate overlying said offset and securing means insertible from beneath the offset in said base plate for clamping said base and joint plates together.

75 6. A rail joint including a base plate extending beneath the rail and provided with an upwardly offset edge and a joint plate overlapping a portion of said base plate and overlying said edge, an elongated opening in said base plate, an approximately registering oval opening in said joint plate, the major axes of said openings being arranged substantially at right angles to each other and securing means traversing said openings.

80 7. A rail joint including a base plate extending beneath and supporting adjacent rail ends, said base plate being of the same cross sectional form from end to end and of less thickness adjacent the wheel flange engaging side of the rail whereby said side of the rail is inclined inwardly away from the wheel

flange that engages a portion of said side, and a flange extending coextensively with said plate and provided with an inclined portion designed to lap the base of the rail continuously from end to end of the plate and to wedge said base against the inclined base plate provided by the varying thickness of said plate.

CHARLES PASCAL.
